(57) **CLAIM**

The ornamental design for a key blank as shown and described.

DESCRIPTION

FIG. 1 is a front elevational view of a key blank showing my new design;

FIG. 2 is a rear elevational view of the design shown in FIG. 1;

FIG. 3 is a front right perspective view of the design shown in FIG. 1;

FIG. 4 is a rear left perspective view of the design shown in FIG. 1;

FIG. 5 is a right side elevational view of the design shown in FIG. 1, the left side being a mirror image thereof;

FIG. 6 is a top plan view of the design shown in FIG. 1; and,

FIG. 7 is a bottom plan view of the design shown in FIG. 1.

1 Claim, 7 Drawing Sheets
